UNITED STATES PATENT OFFICE.

JULIUS R. DROZESKI, OF ERIE, PENNSYLVANIA, ASSIGNOR OF ONE-HALF TO JOHN KOLB, OF ERIE, PENNSYLVANIA.

SPRINKLER-VALVE MECHANISM.

1,136,897.

Specification of Letters Patent. Patented Apr. 20, 1915.

Application filed November 2, 1914. Serial No. 869,833.

To all whom it may concern:

Be it known that I, JULIUS R. DROZESKI, a citizen of the United States, residing at Erie, in the county of Erie and State of Pennsylvania, have invented certain new and useful Improvements in Sprinkler-Valve Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in sprinkler valve mechanism for shower bath apparatus, and has for its object the construction of a valve mechanism adapted to be rotated to direct the direction of the shower, and to be opened and closed by the rotation of the shower nozzle, so that it can be quickly and easily manipulated as desired.

The features of my invention are herein-after fully set forth and explained and illustrated in the accompanying drawings, in which:—

Figure 1, is a side view in elevation of my improved valve mechanism. Fig. 2, is a vertical section of the same on the line $\alpha-\alpha$ looking in the direction of the arrow. Fig. 3, is a front view in elevation, of the same. Fig. 4, is a view of the nozzle valve partly in section on the line $y-y$ in Fig. 2.

In these drawings illustrating my invention, A, indicates the water supply pipe, and B, a yoke secured thereto having a water passage B', in one side thereof communicating with the water supply pipe A. In the inner face of the side of the yoke B, containing the water passage B', there is an opening having a seat b, and in the opposite side of the yoke B, there is a screw threaded opening C, centrally on a line with the opening and seat b. In the screw threaded opening C, there is a knurled plug D, provided with a point d.

Between the seat b, and the point d, of the knurled plug D I mount a hollow cylinder E, having on one side thereof a hollow sleeve F, provided with an internal screw thread F'. The end of the hollow cylinder

E, is provided with an opening e, communicating with the passage B' and with packing e', between it and the seat b, to prevent leakage.

In the hollow cylinder E, opposite the inner end of the hollow sleeve F, there is a valve-seat E', and in the sleeve F, there is a hollow stem G, provided with an external screw thread g, engaging the internal screw thread F', in the hollow sleeve F, the inner end G' of the stem G, being adapted to contact with the valve-seat E'.

The hollow stem G, projects outward through an ordinary stuffing-box H, and is provided with a sprinkler I, provided with sprinkler holes I'. In operation the water is turned on or off by rotating the stem G, so as to bring the inner end G', thereof into or out of contact with the seat E'; and the direction of the shower is controlled by rotating the hollow cylinder E, as desired.

Having thus described my invention so as to enable others to construct and utilize the same, what I claim as new and desire to secure by Letters-Patent is:—

1. In a sprinkler valve mechanism a yoke having a water passage in one side thereof, a hollow cylinder rotatively mounted in said yoke, and connecting with the water passage therein, a hollow sleeve on one side of said cylinder, a valve-seat in said cylinder opposite the inner end of said sleeve, and a hollow stem operating in said sleeve, and adapted to contact with said valve-seat, substantially as set forth.

2. In a valve, a yoke having a water passage in one side thereof, a hollow cylinder mounted in said yoke, and communicating with said passage, a hollow sleeve on one side of said cylinder, a valve-seat in said cylinder opposite the inner end of said stem, and a hollow screw threaded stem adapted to be rotated in said sleeve to bring the inner end thereof into contact with or away from the seat in said cylinder, substantially as set forth.

In testimony whereof I affix my signature, in presence of two witnesses.

JULIUS R. DROZESKI.
